CLAIM

The ornamental design for the garden lamp with square lantern, as shown and described.

DESCRIPTION

FIG. 1 is a perspective view from above of the garden lamp with square lantern in accordance with my design;

FIG. 2 is a front side elevational view of the garden lamp with square lantern in accordance with my design, the rear side being substantially identical thereto;

FIG. 3 is a left side elevational view of the garden lamp with square lantern in accordance with my design, the right side being substantially identical thereof;

FIG. 4 is a top plan view of the garden lamp with square lantern in accordance with my design; and,

FIG. 5 is a bottom plan view of the garden lamp with square lantern in accordance with my design.

The broken lines show solar batteries and a photoresistor and are not considered part of the design claimed.
